DESIGN FOR A HANDBAG

Florence N. Lewis, New York, N. Y.

Application June 15, 1939, Serial No. 85,502

Term of patent 3½ years

To all whom it may concern:

Be it known that I, Florence N. Lewis, a citizen of the United States, residing at New York, in the county of New York and State of New York, have invented a new, original, and ornamental Design for a Handbag, of which the following is a specification, reference being had to the accompanying drawing, forming part thereof.

In the drawing:

Fig. 1 is a front elevational view of a handbag showing my new design;

Fig. 2 is a side elevational view thereof;

Fig. 3 is a rear elevational view thereof with a portion of the handle shown broken away for convenience of illustration;

Fig. 4 is a top plan view thereof, and

Fig. 5 is a fragmentary detailed view of the upper portion of one side of the handbag illustrated in Figs. 1, 2, 3 and 4, from its open position with portions of the handle and body of the bag broken away for convenience of illustration.

I claim:

The ornamental design for a handbag, as shown.

FLORENCE N. LEWIS.
